UNITED STATES PATENT OFFICE.

OSCAR H. HYDE, OF ST. LOUIS, MISSOURI, AND PERRY A. ZIMMERMAN, OF SPRINGFIELD, OHIO, ASSIGNEES, BY MESNE ASSIGNMENTS, TO SAID HYDE.

HOUSE FOR FOWLS.

1,404,963.

Specification of Letters Patent. Patented Jan. 31, 1922.

Application filed October 31, 1918, Serial No. 260,420. Renewed September 17, 1921. Serial No. 501,449.

To all whom it may concern:

Be it known that we, OSCAR H. HYDE, citizen of the United States, residing at St. Louis, in the county of St. Louis and State 5 of Missouri, and PERRY A. ZIMMERMAN, citizen of the United States, residing at Springfield, in the county of Clark and State of Ohio, have invented certain new and useful Improvements in Houses for Fowl, of which 10 the following is a specification.

This invention relates to improvements in structures for housing fowl, particularly chickens.

An object of the invention is to provide 15 a structure of the character referred to which will be simple and convenient in construction and light in character so that it may be readily moved from one point to another in the yard.

20 A further object of the invention is to provide a structure of the character referred to which will be of a knock-down nature so that it can be readily shipped and assembled or taken apart.

25 A further object of the invention is to provide a floor, walls and roofing which will be impervious to heat and cold, but at the same time of light weight and of such 30 nature as to prevent the entrance of such animals as rats and weasels.

In the accompanying drawings:—

Fig. 1 is a perspective view of a structure embodying our improvements, partly broken away.

35 Fig. 2 is a top plan view of the same with the roof removed.

Fig. 3 is a perspective view of the roof broken away to show the interior construction of the same.

40 Fig. 4 is a vertical section of a portion of the roof and one of the side walls and the connection between the two.

Fig. 5 is a transverse section of two of 45 the side walls and the connection between the same.

Fig. 6 is a vertical section of a modification in the roof structure showing the manner of connecting the two roof sections together.

50 Fig. 7 is a transverse section of the side walls, central partition and connections between the same.

Fig. 8 is an enlarged section on the line 8—8 of Fig. 10.

Fig. 9 is an enlarged section on the line 55 9—9 of Fig. 10.

Fig. 10 is a side elevation with the lower portion of the rear compartment broken away to show a modification in the nature 60 of a floor.

Referring to the drawings, the structure consists of side walls, a rear wall, a front frame and central partition and two roof sections indicated in a general way by a, b, 65 c, d, e, f, g, h and i. The upper edges of the side walls b and d, slant downward in a rearward direction while the upper edges of the side walls, a and c, slant downward in a forward direction. The height of the rear side walls, b and d, is greater than that of 70 the forward side walls, a and c, so as to provide a ventilating space above the roof, h, which has hinged windows l which may be opened to furnish ventilation to the rear compartment of the structure. One of the 75 rear side walls, such as d, has a door 2, the central partition is also provided with a door 3 and the front side walls are provided with a series of windows 4. The rear side wall, b, also has a window 5, and a window 80 6, shown in dotted lines in Fig. 1, is placed in the rear wall e.

One of the features of our invention is the manner of constructing the various side walls, central partition and roof sections. 85 This construction is shown in Figs. 3 to 7 inclusive. Each side wall consists of an outer and inner layer, 7 and 8, respectively, of what is commercially known as double faced corrugated strawboard between which 90 is placed a wire screen 9. Each straw-board layer is of the usual construction consisting of flat side sheets and an inner crimped or corrugated sheet pasted together. These layers of strawboard and wire screen are bound 95 together about their edges by outer and inner metallic strips 10 and 11 respectively, rivets 12 being employed for firmly securing all the layers together.

Each of the roof sections is constructed 100 with upper and lower sheets of the same strawboard, represented by 13 and 14 between which is placed a wire screen 15 of a similar nature, but in addition thereto has an outer layer of tar paper 16 to provide a more complete protection against rain, although all of the strawboard is coated with a weather resisting paint such as an 105

asphaltum paint, creosote or ingredients of a similar nature which also act as a preventive against vermin.

The central partition, shown in Fig. 7 is 5 similarly constructed of layers of strawboard 17 and 18 with an intermediate wire screen 19, the strawboard being treated in a similar manner.

The manner of connecting these sections 10 together is as follows:—

Each of the outer sheet metal binding strips 10 of the side walls is extended beyond the walls proper, the vertical side strips being secured by removable bolts or 15 screws 20 to vertical T-irons 21, 22, 23, 24, 25 and 26, any suitable number of these bolts being employed, the central T-irons 23 and 24 being secured together by the bolts 27, this construction being illustrated 20 in Figs. 2, 5 and 7.

The different layers of the central partition are bound together by metallic strips 28 and 29, the upper and lower strips 28, being extended, as shown in Figs. 2 and 7 and secured to the T-irons 26 by the bolts 27 before referred to.

The strawboard and wire screen layers of the roof are bound together by the outer and inner metallic strips 30 and 31 and rivets 33. 30 The outer strips 30 have their outer edges bent downwardly at right-angles as indicated at 30^a, which portions 30^a are connected to the top strips 10 of the sides of the structure by the bolts 32.

35 In Fig. 6 is shown a slight modification illustrating the manner of connecting together two roof sections in the event it is desired to enlarge the capacity of the structure, this being accomplished by simply securing 40 together the vertically-extending portions 30^a of each roof section by the bolts 32; a water proof packing 34 being preferably inserted between the flanges 30^a.

By this construction it will be seen that 45 the house can be transported in knocked-down state and readily assembled by connecting the metallic strips of the various side and back and front sections and the two roof sections by the bolts 20, 27 and 32. Owing 50 to the light construction of the walls and roof sections the entire structure when assembled can be moved from place to place in the chicken yard as desired. The rear enclosure formed by the side walls, *b* and *d*, and end wall, *e*, partition, *g*, and roof section, *i*, forms a roosting and laying compartment for the fowl, while the front compartment formed by the side walls *a* and *c*, partition *g*, roof sections *h* and front screen 55 *f*, forms a runway or scratching compartment.

The construction of the various walls and roof sections afford a simple, light, cheap and sanitary structure, impervious to both 60 heat and cold, and also to the entrance of ro-

dents such as rats and weasels, the lightness of the walls and roof enabling the structure to be readily transported from place to place without disassembling the house.

In Figs. 8, 9 and 10 the rear compartment of the structure is shown provided with a floor. This floor is constructed like the side walls and the roof; that is, there are provided upper and lower layers 35 and 36 of corrugated double faced strawboard 75 and an intermediate layer of wire mesh or screen. In this case the lower edge of the central partition *g* is equipped with an angle iron 38 and the side walls with similar angle irons 39 (Fig. 10) along their lower edges, 80 and the rear wall with a similar angle iron 40. The floor rests upon the angle irons of the partition and side walls, being secured thereto by bolts 41, but is hung to the angle iron of the rear wall, being secured thereto 85 by the bolts 42. In the structure where a floor is employed the rear wall will not extend down to the ground line, but an open space will be provided beneath the lower edge of the rear wall so that by removing 90 the bolts the floor can be removed by drawing it out under the lower edge of the rear wall. This construction enables the floor to be removed without displacing the structure 95 for cleaning purposes. It might be mentioned that the front and side edges of the floor are provided on their under sides with a projection strip 43 and the rear edge of the floor or its upper side projected with a projecting strip 44 which furnishes the means 100 of attaching the floor to the angle irons.

Having thus described my invention, I claim:—

1. A wall for a house structure consisting of outer and inner layers of double faced strawboard, and a central layer of wire screen, together with means for connecting the same together, each layer of strawboard consisting of an outer and inner flat sheet connected to a central corrugated sheet. 105

2. In a structure of the character described, side wall sections, a rear end section and roof sections, each section consisting of outer layers of fibrous material and an inner layer of metallic screen, and outer and inner metallic bands for clamping the fibrous material and screens together, the outer bands of each section being extended, together with devices for removably securing the extended portions of the bands together. 115

3. In a structure of the character described, side wall sections, a rear end section and roof sections, each section composed of outer layers of fibrous material and an inner layer of metallic substance, together with metallic bands about the edges thereof for clamping the same together, the band on one side being extended beyond the section, upright metallic supports between adjacent side and end sections, means for removably securing the 125

extended edges of said bands with said upright supports, and for securing the extended edges of the bands of the roof sections to the extended edges of the bands on the upper 5 edges of the side and end sections.

4. A wall for a house structure, consisting of outer and inner layers of fibrous material and a central layer of metallic screen, and bands about the inner and outer edges of the 10 same for clamping the layers together, the bands on one side of the wall being extended to provide means of attachment.

5. In a structure of the character described, side wall sections, a rear end section and roof 15 sections, each section consisting of outer lay-

ers of fibrous material and an inner layer of metallic screen, outer and inner metallic bands for clamping the fibrous material and screens together, the outer bands of each section being extended, together with devices 20 for removably securing the extended portions of the bands together and a removable floor for said structure.

In testimony whereof, the said OSCAR H. HYDE has hereunto set his hand this 5th day 25 of October, 1918, and said PERRY A. ZIMMERMAN has hereunto set his hand this 9th day of October, 1918.

OSCAR H. HYDE.

PERRY A. ZIMMERMAN.
